TELEGRAPH TRANSMITTER

Louis M. Potts, Evanston, Ill., assignor to Teletype Corporation, Chicago, Ill., a corporation of Delaware

Application December 31, 1936, Serial No. 118,516
Renewed May 20, 1939

21 Claims. (Cl. 178—79)

The present invention relates to telegraph apparatus and is concerned more particularly with keyboard mechanisms for the transmission of synchronized monopulse signals.

5 The principal object of the present invention is the provision of a transmitter of simple and compact design, which is positive and efficient in its operation and inexpensive in construction.

A feature of the invention resides in the transmission of monopulse synchronous signals having an interval of predetermined constant duration in which its characteristic is distinguishable by its period of occurrence relative to a synchronously controlled cyclic period.

15 In its essential embodiment, the present invention contemplates a transmitting mechanism especially adapted for generating monopulse synchronous code signals to be used in the control and operation of telegraph printers of the class described and illustrated in copending application Serial No. 215,343, filed June 23, 1938.

A continuously rotating and synchronously controlled main operating shaft carries a revolving seeker which traverses a circumferential path adjacently surrounded by a plurality of keylever controlled interceptor elements which control the transmission of the monopulse signals. Each of said elements, which is normally maintained in a non-interference position, is 25 designed to be shifted slightly upon the operation of its associated manual key. A particular key upon being actuated also causes to be dislodged a locking means which intervenes to prevent the actuation of any other key during the time that 30 the particular key is actuated. When, after a key operation, a revolving seeker carried by the synchronously controlled shaft encounters the dislodged interceptor element, it causes to be momentarily opened a pair of contacts and also 35 after the lapse of a constant time interval to be restored both the interceptor element as well as its associated actuating key. The period during each synchronized cycle when the afore-described circuit interruption or signal occurs 40 characterizes the letter, figure, or other function which has been selected.

For a more comprehensive understanding of the several features and the structure of the present invention, reference should be had to the accompanying drawings and to the following detailed specification wherein like reference characters have been employed to designate corresponding parts throughout, and wherein;

Fig. 1 is an exploded perspective view of a transmitter apparatus having embodied therein

certain principles concerned in the present invention;

Fig. 2 is a cross-sectional view taken approximately on line 2—2 of Fig. 5;

Fig. 3 is a fragmentary side elevational view 5 of the mechanism shown in Figs. 2 and 5 with the cover wall broken away;

Fig. 4 is a diagrammatic chart which graphically shows a typical signal (the alphabetical character K) such as is employed in the control of apparatus for which the present invention 10 is particularly adapted; and,

Fig. 5 is a plan view of a transmitting mechanism such as is featured in the foregoing figures having certain portions thereof broken away to 15 reveal the posterior structure.

In the drawings the reference character 11 denotes a cylindrical cup which serves as a housing and with its bottom wall 12 completely surrounds the transmitter operating mechanism. A 20 cover plate 13 is fitted over the brim of the housing cup 11, and therethrough arranged in concentric circles are two rows of manual keytops 14. The outermost row of keytops have vertically extending bars 15 with short cam projection 16, 25 while the innermost rows have corresponding bars 17 (left side of Fig. 2) with longer cam projection 18. The difference in the length between projections 16 and 18 is sufficient to compensate for the difference in the respective distances between the center of the unit and the two rows of key bars so that the extremities of projections 18 30 extend out and align peripherally with the extremities of projections 16.

In a circular arrangement about the vertical 35 bars 15 and 17 are a plurality of interpositioned elements or signal actuators 19, each one of which is associated with one of the key bars 15 or 17 and has a cam projection 21 that aligns with and abuts the extremity of the aforementioned projections 16 and 18. A garter spring 22 which encircles the several interposition elements 19 urges them inwardly until their cam projections 21 are butted against the key bar projections 16 and 18. While in this position, the 40 offset extremity 24 of each bar 15 or 17 is disposed beneath the skirting flange of bell disc 23, and its vertical or main body portion is withheld against the influence of garter spring 22 so as to clear the peripheral extremity of the blocking 45 lugs 26, as best indicated in Fig. 2. When one of the key bars 15 or 17 is depressed, its projection 16 or 18 moves far enough below its associated projection 21 on interposition element 19 to permit the latter to respond to the influence of the 50 55

garter spring 22 and be rocked or shifted inwardly with its disc extremity 23 as a pivot, and with its offset extremity 24 moving the greatest distance and there entering the space aligning vertically with it between two of the adjacent lugs 64. Because the discs 23 are seated in rectangular slots 25 in the cover plate 13, interposition elements 19 may not be expected to rock upon accurate centers especially since their vertical 10 suspension is dependent upon the support afforded by cross pins 26. This construction has been found satisfactory in operation, and by reason of its simplicity, to be economical in manufacture and assembly.

15 The extremity of each key bar 15 and 17 is angularly bent at 27 as may best be noted in Fig. 3, and the extremity of each bent portion 27 lies above an associated opening 28 in a locking disc 29 when said disc is in its normal (counterclockwise extreme) position. The several openings 28 are staggered to correspond with the disposition of the several extremities 27, and upon the actuation of any key bar 15 or 17, the engagement between the foremost surface of its inclined portion 27 with a contiguous surface on a deflected portion 31 struck to form the opening 28, causes locking disc 29 to be cammed in a clockwise direction, as viewed in Fig. 5, in opposition to its return spring 32 which is anchored 30 at 33 to a relatively stationary portion of the unit. This rotational displacement of locking disc 29 causes to be offset its several openings 28 sufficiently so that all of others of them, excepting the one which has been entered by the 35 actuated key bar, are no longer in alignment with their associated angled portion 27, and if thereafter any other key bar 15 or 17 is attempted to be depressed, the operation is blocked when the extremity of its angled portion 27 abuts the solid surface of the locking disc 29.

40 Upon the depression of a key bar and the consequent rotation of the locking disc 29, the condition thus established is latched momentarily pending the transmission of the signal which is not executed until a seeker yoke 47 passes the 45 proximity of the depressed key bar and its related interposition element 19. The lowermost shoulder of cam projection 21 overlies the upper shoulder of key bar projections 16 or 18 when the former is in its innermost or effective condition, and thereby prevents return spring 62 from restoring the actuated key bar, and since the garter spring 22 urges interposition elements 19 inwardly, this latched condition prevails until 55 said interposition elements 19 are restored to normal by a device to be described later.

Secured by means of the screws 330 to the cover plate 13 is a supporting disc 34 whose radial flange 35 is slotted at several places 36, Fig. 5, to receive innermost the vertical interposition bars 15 and 17 and outermost the interposition elements 19 aforescribed. Between the rigid disc 34 and cover plate 13 there is firmly gripped a thin supporting disc 37 which is also radially slotted in alignment with the aforementioned slots 36 to receive the vertical bars 15 and 17 as well as interposition elements 19. Accordingly, with the slots in radial flange 35 and those in supporting disc 37 affording lateral support to the several elements 15, 17, and 19, a relatively flexible assembly unit having nevertheless few moving parts is attained.

In the featured embodiment, a bushing 38 is fitted through discs 34 and 29 which serves as a 75 journal for the extremity of a synchronously

driven shaft 39 and has a pivot sleeve for the reciprocable discs 28, 63, and a slideable disc 41 to be described later. As shaft 31 rotates, it carries with it a collar 42 which is secured to it by means of a set screw 43, and the arm 44 which is integrally formed with the collar 42. Upon arm 44 is mounted a trunnion block 45 through which extends the shaft 46 and the ends of the latter protrude through a pair of ears 50, Fig. 1, which are integrally formed with the shafts 49 of a 10 yoke 47, Fig. 1. In this arrangement, yoke 47 is supported for limited reciprocal movement by an adjustment screw 48 whose head protrudes through a small opening in the yoke 47, and determines the clockwise limit of movement, while 15 the corners of the pivotal ears of shafts 49 limit the counterclockwise extent of movement of yoke 47. The shafts 49 of yoke 47 straddle the bushing 38 and terminate with slightly upturned nibs which rest against the bottom of slideable disc 20 41. The main shaft of yoke 47 extending radially from the pivotal center of the assembly terminates with a T-shaped structure which supports two cam elements. A vertically acting cam body 51 is a narrow segment whose fore portion 25 flares downwardly and is disposed to ride under the offset extremities 24 of any interposition element 19 which is found in its selected or innermost position. Since the plateau section of cam 51 is normally in horizontal alignment with the 30 projections 24, as may be noted in Fig. 2, it will be understood that in the event any key member 14 is depressed at the instant when the response of its interposition element 19 in moving inwardly would encounter the plateau section of cam segment 51, the blocking of the square shoulder 24 by said plateau section of segment 51 will prevent the instantaneous selection or movement into selected position of such interponent 19 but instead will put off the selection until the seeker 40 47 shall have passed the proximity of such interponent 19. The contingency of such an occurrence, however remote, must be noted as possible and in order to prevent the consummation of an interponent selection under these circumstances 45 and the resultant fore-shortening of the signal period, the peripheral surface of cam segment 51 is utilized in the momentary blocking of the selector. Immediately that the cam segment passes the proximity of such interponent 19, 50 however, the latter is free to resume its normal movement under impetus of the garter spring 22, so that upon the subsequent passing-by of the seeker, its cam 51 will ride under projection 24 generating a full length signal in the normal 55 manner of operation. Another cam 52 is provided with a sidewardly inclined surface 53 which, as the assembly rotates (clockwise as viewed in Fig. 5), engages the adjacent surface 60 of offset extremity 24 and cams the latter outwardly and back into its normal or non-active position.

Extending perpendicularly from the slideable disc 41 are three parallel guide legs indicated 54, 55, and 56. The three legs extend through snugly chambered openings in the supporting disc 34 and maintain parallel vertical movement of slideable disc 41. One of the legs 54 terminates with a contact actuating projection 57 which, when slideable disc 41 is moved upwardly, causes, 70 through its engagement with an insulated block on the contact element 58, an electrical separation of the latter from its associated contact element 59. After cam 51 has passed over the offset extremity 24, cam 52 inaugurates the restoration 75

of a particularly selected interposition element 19, and when finally restored, cam 51 rides off the projection 24 and resumes its normal position under impetus of a set of springs 61 one of which surrounds each of the guide legs 54, 55, and 56, urging the slideable disc 41 downwardly and moving through the shaft 49, the yoke 47 clockwise.

During this period, while yoke 47 is cammed out into its counterclockwise position and contact pair 58-59 is open, there is impressed upon the line a condition termed the signal interval, which, in the instant embodiment, contemplates a "no current" electrical condition, but which by transposing the contact bars 58-59 and normally maintaining them ajar, may be employed in accordance with a reverse system of operation where the normal line is open and the signal interval constitutes a closed or "current" line condition.

A bell disc 63 is supported immediately beneath locking disc 29 for limited reciprocal rotation about bushing 38. The two discs 29 and 63 are held by a pair of shouldered screws which may be threaded into the supporting member 34 and which extend through arcuate slots in both discs 29 and 63. The periphery of bell disc 63 is studded with spaced lugs 64 each associated with one of the interposition elements 19. A spring 65, Fig. 5, connecting an ear 66 integrally formed with bell disc 63 and one 67 integrally formed with locking disc 29, urges disc 63 in a counterclockwise direction, and disc 29 in a clockwise direction until a pin 30 which extends perpendicularly from disc 29 into an elongated slot 40 of the bell disc 63 strikes the leftward extremity, Fig. 5, of said slot. While, as will be noted later, spring 65 is tensioned by the movement of disc 29 clockwise and pulls disc 63 in the same direction, the restoration of disc 29 is not through spring 65 but rather through the tenser spring 32.

Upon the camming out of an interposition element 19 restoring it to its normal position, cam projection 21 is withdrawn from interfering with the projection of its associated feed bar 15 or 17. Accordingly, the latter is also freed as a consequence of the primary stimulus initiated by yoke 47 and thereupon responds to the urge of its individual return spring 62, resumes its normal position, and withdraws its angled portion 27 from resting against the deflected portion 31 of locking disc 29. The freeing of disc 29 permits it to respond to the return spring 32 rocking counterclockwise or until the several openings 28 are again brought into alignment with the angled portions 27 of all of the key bars 15 and 17.

The stop means 30 for limiting the counterclockwise movement of locking disc 29, Fig. 5, which passes through an elongated hole 40 in disc 63 serves merely for limiting the counterclockwise movement of disc 29 with respect to disc 63 but for limiting the counterclockwise movement of both of said discs, suitable limiting pins are contemplated which may pass through elongated holes in both discs or in disc 63 alone and which are anchored in the supporting disc 34. When locking disc 29 is urged clockwise pursuant to the depression of a key bar 15 or 17, tension is stored in spring 65 and by it in turn communicated to bell disc 63, but there movement is resisted when a tooth 68 integrally formed with slideable disc 41 encounters a floating lug 69 which is carried by a strip of spring steel 71 secured to the bell disc 63 at 72. When

a key bar is depressed, the resultant clockwise movement of locking disc 29 distends the restorative spring 32 as well as spring 65.

In its normal position, bell disc 63 is so disposed that the peripheral notches thereof which intervene the lugs 64 align opposite the ends 24 of interposition elements 19 permitting any one of the interposition elements 19 to assume readily its effective condition upon the actuation of its associated key bar 15 or 17. Thereafter, when slideable disc 41 is raised by the action of yoke 47, floating lug 69 is freed, and accordingly bell disc 63 is permitted to rock in a clockwise direction as influenced by spring 65 until the particular tooth 64 adjacent to the actuated one of the interposition elements 19 encounters and is arrested thereby. An interposition element 19 is cammed out by the side cam 52, and when its tooth 24 clears the lugs 64, bell disc 63 is free to move farther in a clockwise direction presenting a lug 64 directly behind the element 19 and preventing said element from resuming its selected position after the side cam 52 has moved by. This it would otherwise tend to do especially if a key bar 15 or 17 happened to be continuously depressed as by a lingering manipulation.

Accordingly, the function of bell disc 63 will be observed as one of preventing a multiplicity of signals from being issued in response to a single prolonged key bar actuation and requiring instead that, where a number of signals are desired, an operator be required to impart a corresponding number of manipulations. It will be recalled that upon rotating locking disc 29 clockwise, a certain tension was stored up in the restorative spring 32. This force is free to move disc 29 in a counterclockwise direction as soon as the actuating key bar 15 or 17 is returned to normal. At an intermediate point in the restoration of disc 29, the limiting pin 30 encounters the end wall of slot 40 and from that point onward carries along the bell disc 63 until both discs arrive at the original position shown in Fig. 5 and at which the discs are limited by a stop lug (not shown) which extends from the supporting disc 34.

Operation

The embodiment of the present invention herein disclosed contemplates, as has been said, a mode of signal transmission which may be best understood by referring to the accompanying Fig. 4 where a cycle of rotation of shaft 39 may be interpreted as the linear distance between any one of the alphabetical or numerical characters illustrated in this figure, and the point thereafter at which that character first recurs. When no signals are transmitted, a continuous current condition prevails which is symbolized by the shaded section 73 occurring above the median line 74. On the other hand, during a signal interval, the current condition is interrupted and is indicated in Fig. 4 by the shaded section 75 occurring below the median line 74. The length of the signal interval 75 is dependent, of course, upon the interval duration between the instant when offset extremity 24, acting upon cam 51, cause yoke 47 to raise disc 41 and its leg 54 sufficiently to break the connection between the contact bar 58-59 and the instant when side cam 52, returning interposition elements 19, permits cam 51 to jump back together with its yoke 47 and by the same mechanical train permitting contact pair 58-59 to resume its close contractual relationship.

This interval has been made of substantial extent, as indicated by the length of the shaded section 75 illustrated in Fig. 4, in order that the created line signals may not tend to become weakened. This practice limits the closeness of consecutive signals to such a minimum that at least five characters, in terms of radial distance, are required to intervene consecutive transmitted character signals, and where characters more closely situated upon the transmitter periphery are attempted their transmission may accordingly require separate cycles of transmitter rotation.

The depression of any key bar 15 or 17 is effected by pressing the finger upon one of the manual keys 14 which carries upon its upper surface a legend indicating the character which it represents. In response to the downward movement of the key bar proper, two results are obtained. In the first place, locking disc 29 is cammed clockwise, as viewed in Fig. 5, and in prompt succession an associated interposition element 19 is afforded a clearance by the withdrawal of the key bar projection 16 or 18 so that garter spring 22 will urge said particular interposition element 19 centripetally into its effective position whereat its lowermost extremity 24 will occupy a space between two of the spacing lugs 64.

Meanwhile, it will be recalled, shaft 39 is in continuous rotation carrying with it yoke 47 which seeks out any selected interposition element 19, and upon encountering one of them in its centripetal station, is cammed away causing 35 to be tilted its inwardly extending shafts 49. The clockwise rotation of locking disc 29 imparts a tension to spring 65 because its other end, which is secured to ear 66, fails to respond and follow in the clockwise movement of locking disc 29. This 40 is due to the blocking engagement of floating lug 69 and tooth 68 of slideable disc 41.

As the shafts 49 of yoke 47 tilt upwardly, they cause to be hoisted the slideable disc 41 until projection 68 is moved clear of the floating lug 69, 45 while at the same time contact actuating projection 57 encounters and opens the contact pair 58-59. As a result of the freeing of bell disc 63, the latter rotates about a half tooth distance (about half the width of one of the spacing lugs 50 or teeth 64). The period occupied by cam 51 in passing the proximity of the interposition element 19, while relatively short, is equivalent nevertheless in the present embodiment to the peripheral distance of approximately five consecutive 55 interposition elements 19. Towards the end of the period of its effective encounter, with an element 19, side cam 53 moves away the selected interposition element 19 which had been occupying the space between consecutive teeth or lugs 64 60 permitting bell disc 63 to move the remainder of a short angular distance, and in so doing to prevent the particular element 19 from reentering. The purpose of blocking lug 68 therefore will be understood as one of preventing the rotation of bell disc 63 in response to the urge of spring 65 until 65 after a particular interponent 19 has had an opportunity to enter its associated peripheral clearance between a pair of lugs 64.

Following this, the slideable disc 41 is elevated, 70 latch tooth 68 removed from the field, and the force of spring 65 permitted to rotate bell disc 63 until its progress is retarded by the extremity of the very interponent 19 which had selected.

After said interponent is displaced by the side 75 cam 53 and thereby caused to resume its normal

position, bell disc 63 is permitted to move farther in the clockwise direction as urged by spring 65 so that the interponent 19 having been cammed out may not reenter and permit a second signal to be generated. A plurality of depressions of the 5 manipulators 15 or 17 is therefore essential to effect a plurality of character signals, and the continued depression of any of said manipulation plungers does not produce more than one signal.

The restoration of the particular interposition 10 element 19 withdrawing its cam projection 21 permits its associated key bar 15 or 17 to respond to the urge of its return spring 62 and resumes its elevated or normal position in readiness for a 15 succeeding operation.

While the present invention has been explained and described in contemplation of a specific embodiment, it is to be understood that numerous modifications and variations may be made without departing from the spirit of the present invention. Accordingly, it is not intended to be limited to the specific details of the accompanying drawings nor to the language of the foregoing specification except as indicated by the herein-after appended claims.

What is claimed is:

1. A transmitter including a plurality of key bars arranged in a circle, a disc having a plurality of vanes each associated with one of said key bars, and actuating means carried by each key bar for 30 rotating said disc by engagement with a vane to prevent the actuation of any other of said key bars pending the restoration of an actuated key bar.

2. In a keyboard transmitting mechanism, a 35 circuit breaker, a plurality of key bars, a corresponding plurality of circuit breaker actuating means, each under the control of one of said key bars, and a device actuated by a conditioned one of said plurality of actuating means for operating 40 said circuit breaker and for restoring said conditioned one of said plurality of actuating means.

3. The combination set forth in claim 2 in which said operating device includes means to both operate said circuit breaker and restore one 45 of said actuators within the same cyclic time intervals.

4. A keyboard transmitter mechanism, including a circular arrangement of manipulators, a circular arrangement of signal initiating elements 50 each associated with and conditioned by one of said manipulators, a continuously revolving apparatus traversing the proximity of said signal initiating elements for impressing current conditions upon a line and actuatable by a conditioned 55 one of said elements, means under the control of said revolving apparatus for restoring each conditioned one of said elements following its control of said revolving apparatus, and means for preventing the reconditioning of one of said elements 60 after its restoration in the event of a continuous operation of its associated manipulator.

5. In a transmitting mechanism, a rotatable member, a portion movable longitudinally along the axis of rotation of said member into alternative positions, a circuit breaker opened and closed by said longitudinally movable portion in accordance with its alternative positions, and a plurality of conditionable means arranged about said rotatable member for shifting said portion from one 70 to another of its alternative positions.

6. In a transmitting mechanism, a circuit breaker associated with a signaling line, a rotatable member having a reciprocable portion, a plurality of manipulation means, an element under 75

- the control of each of said plurality of means for encountering said reciprocable portion and for rocking the latter to actuate said circuit breaker, and apparatus carried by said reciprocable portion for restoring any of said elements following its encounter by said reciprocable portion.
7. A keyboard transmitter comprising in combination, a plurality of key members, a circular arrangement of actuators controlled by said members, each having a key member latching portion and a trip portion, a revolving apparatus carrying a shiftable arm to be encountered by said trip portion, a line switch actuated by said shiftable arm when the latter encounters one of said actuator trip portions, and means carried by said revolving apparatus for restoring any of said actuators to a neutral position after the lapse of a predetermined time interval.
8. In a transmitting mechanism, a plurality of key members, a contact controlling device, means under the control of any one of said plurality of key members for actuating said contact controlling device, and a member responsive to a prolonged manipulation of any of said key members for preventing repeated operation of said contact controlling device.
9. In a keyboard device, a plurality of key members operatively supported in a concentric alignment, a locking disc including appurtenances to cooperate with each of said key members to be shifted together with said locking disc upon the actuation of any one of said key members, and means associated with said locking disc effective during the shift disposition thereof and following the actuation of one of said key members to prevent the operation of any of the other of said key members.
10. In a keyboard device, a plurality of key members, a locking disc, cam means associated with said key members and said disc for rotating said disc into a locking position, and means for restoring said disc to its normal position upon the release of an actuated key member.
11. A keyboard transmitter comprising a circular assembly of key members, a locking device actuatable upon the depression of one of said key members to prevent the actuation of any other of said key members, a plurality of signal transmitting elements, each associated with one of said key members and conditionable by the actuation thereof, and a repeat signal preventing means comprising a blocking apparatus normally disposed to permit a selective disposition of one of said transmitting elements but shiftable immediately following a signal transmission to prevent the reconditioning of said conditioned one of said transmitting elements.
12. A keyboard transmitting apparatus comprising a synchronously regulated and continuously rotated shaft, a seeker carried by said shaft and capable of being reciprocated to effect alternative line controlling conditions, a plurality of signaling elements disposed along the path of said rotating seeker and individually conditionable to encounter said seeker and to cause its reciprocation thereby, means associated with said seeker for restoring conditioned ones of said signaling elements following their encounter with said seeker, and means for preventing the repeated conditioning of said elements.
13. A transmitting mechanism comprising a continuously rotating shaft, a plurality of key members operatively supported in concentric alignment about said shaft, a plurality of signaling elements each associated with one of said key
- members and disposed in concentric alignment about said shaft, a contact controlling member carried by said shaft, and revolvable through a path defined by said signaling elements, means under the control of each of said key members for moving one of said elements into the path of said revolvable member, and means associated with said member for automatically restoring moved ones of said signaling elements following their encounter with said member.
14. In a rotary switch controlling apparatus, a rotatable shaft, a plurality of character members, means carried by said shaft having itinerant communication with said character members, a circuit breaker, a circuit breaker controlling device operable by said means when the latter is conditioned by any of said members, and a portion carried by said means for restoring operated ones of said members.
15. In a keyboard control apparatus, a plurality of actuatable manipulators, a shaft driven with cyclic regularity, a signaling switch, a supervisory member for controlling said switch, latchable means for prolonging the supervisory effects of actuating any of said manipulators, means carried by said shaft for restoring said prolongation means to non-actuable position following an operation of said signaling switch, and a device for preventing said prolongation means from reentering its actuated position after having been restored through its manipulator is continuously maintained in actuating position.
16. In a rotary control device, a circular arrangement of centripetally urged interponents, a shiftable disc having a blocking portion and an adjacent clearance presentable alternately for each of said interponents, a latch for holding said disc so as to present its clearances to said interponents, and means for releasing said latch after one of its said clearances has been entered by its interponent.
17. The combination set forth in claim 16 including a switch controller with which said latch is integrally associated.
18. In a rotary control device, a circular arrangement of manipulators, an interponent associated with each of said manipulators, a rotatable shaft, means carried by said shaft having itinerant communication with each of said interponents, a shiftable disc carried by said shaft having a blocking portion and an adjacent clearance portion presentable alternatively for each of said interponents, a latch controlled by said rotary device for retaining said disc in a position so as to present its clearance portions to their associated interponents, and means operative following the actuation of one of said manipulators for releasing said latch after the associated interponent has entered its clearance portion in said disc.
19. In a telegraph transmitting apparatus, a set of character members for initiating the transmission of corresponding character signals, interponent means conditionable by said character members for determining the cyclic periodicity of character signals, a transmitting distributor including a rotatable member, and means including said rotatable member and said interponent means for preventing the generation of partial signals.
20. In a telegraph transmitting apparatus, a set of character members each manually depressable for signal control actuation, a rotary distributor, and interponent means conditioned and operated upon the depression of any one of said character

members for communicating through said rotary distributor a character variation of definite length indicative by its periodicity in the cycle of said distributor of a corresponding signal characteristic.

5. 21. In a signal transmitting apparatus, a keyboard comprising a set of key members, a distributor, a device traversing said distributor in regu-

lar cyclic rotation, means under the control of each of said key members for conditioning said device for operation before or after a characteristic interval in its rotation, and means for preventing the conditioning of said device from being initiated during a precise instant in its rotation characteristic of a particular signal.

LOUIS M. POTTS.
